United States Patent Office.

WILLIAM MASTERS, OF NEW YORK, N. Y.

Design No. 2,824, dated November 5, 1867.

DESIGN FOR A SMOKING PIPE.

The Schedule referred to in these Letters Patent and making part of the same.

TO ALL WHOM IT MAY CONCERN:

Be it known that I, WILLIAM MASTERS, of the city, county, and State of New York, have originated and useful Design for Smoking Pipes, of which the following is a full, clear, and exact description, referring being had to the accompanying drawing, forming part of this specification, and in which—

Figures 1 and 2 represent opposite side views of a pipe covering, ornamented with or made according the design herein referred to.

The design, which is arranged on the bowl portion of the pipe, is made up of emblems or symbols of masonic type or character, the same consisting, on one side of the pipe, as represented in fig. 1, of two pillars surmounted each by a globe, with an "all-seeing eye" between them, compasses and square crossing each other and enclosing the letter G, together with a trowel and star below a line, connecting the two pillars at their bases and outside of either pillar, near their bottom, a "fleur de lis," surmounted by a star, while the opposite side of the bowl is ornamented, as represented in fig. 2, with a building, which may be termed Solomon's temple surmounted by a globe and instrument having three legs, and resting on a ground base having a star below and terminating at either end in a "fleur de lis," with star above.

What I claim as my invention, and desire to secure by Letters Patent, is—

The design for smoking pipes herein shown and described.

WM. MASTERS.
